UNITED STATES PATENT OFFICE.

HELEN E. LEIGHTON, OF BOSTON, MASSACHUSETTS.

SANITARY PAD FOR WATER-CLOSET SEATS.

1,283,533.

Specification of Letters Patent. Patented Nov. 5, 1918.

Application filed September 28, 1917. Serial No. 193,653.

To all whom it may concern:

Be it known that I, HELEN E. LEIGHTON, a citizen of the United States, residing at Boston, in the county of Suffolk, in the 5 State of Massachusetts, have invented a certain new and useful Improvement in Sanitary Pads for Water-Closet Seats, of which the following is a specification, reference being had to the accompanying drawings.

10 The object of this invention is to provide a protective and sanitary cover for water closet seats and more particularly for the seats of public closets which are used promiscuously, and my improvement consists essentially of a pad made up of a plurality of tissue, or semi-tissue, sheets which are molded to conform to the contour of the molded seat; the arrangement being such that the upper sheet of said pad may be 15 readily torn off and destroyed after having been once used, thus leaving the next exposed top sheet of the pad ready for use when needed.

My invention is illustrated in and by 20 the annexed drawings in which Figure 1 is a perspective view of a water closet seat showing a pad of my present improved form and construction mounted on the said seat. Fig. 2 is a central, vertical, sectional view of the water closet bowl and seat with the pad mounted thereon and Fig. 3 is a 25 relatively enlarged top view of the said pad.

Referring to these drawings, the letter 30 *a* indicates a water closet seat of ordinary molded construction, mounted upon the bowl *b*. My improved sanitary pad is indicated as a whole by the letter *c* and it consists of a number of sheets which are cut to substantially the same shape as the said seat 35 but somewhat large; the outer and inner edges of the pad thus provided being slotted

radially, as at *d*, and conformed, under pressure, to lap around or rather under, the outer and inner edges of the seat, as 40 will be best understood by reference to Fig. 2 of the drawings; the pad being thus supported in proper position on said seat. The front edge portions of the padded sheets are formed as extended flaps *e* by means of which 45 the sheets may be readily and successively grasped and torn off after use. In making up and molding the pad so that it will be held in position on the water closet seat I may gum together the successive slotted portions of the pad and then mold the same before the gum sets, thus providing in the finished pad, turned in edge portions that hook under the water closet seat and are 50 stiff enough to retain the pad in its operative 55 position while the pad is in use and while the sheets are being torn off one at a time.

My described device costs very little to produce, it is always in place ready for use and it provides a clean and sanitary seat for 60 each and every user of the water closet.

Having thus described my invention, I claim as new and wish to secure by Letters Patent:—

In combination with a water-closet seat, 70 a sanitary pad including a plurality of sheets conformed to the general outline of the closet-seat and having slotted marginal edges and said slotted marginal edges being coated with an adhesive and adapted to be 75 molded inwardly upon the underside of the closet-seat, the adhesive upon said edges being plastic as said edges are molded inwardly to provide for their adherence to the closet-seat, said pad of sheets terminating in 80 extended flaps to serve as finger-holds for grasping an individual attachment of the sheets.

HELEN E. LEIGHTON.
